UNITED STATES PATENT OFFICE.

WILLIAM ELLIS JEFFERSON, OF NOTTINGHAM, COUNTY OF NOTTINGHAM, ENGLAND, ASSIGNOR OF ONE-HALF TO EDWIN B. STIMPSON, OF BROOKLYN, NEW YORK.

ELASTIC WOVEN FABRIC.

SPECIFICATION forming part of Letters Patent No. 314,581, dated March 31, 1885.

Application filed November 10, 1883. (No model.)

To all whom it may concern:

Be it known that I, WILLIAM E. JEFFERSON, a British subject, residing at Nottingham, in the county of Nottingham, England, have 5 invented a new and useful Improvement in Elastic Woven Fabrics, of which the following is a specification, reference being had to the accompanying drawings.

In the manufacture of boots and shoes composed in part of the elastic woven fabric now in use, there are apt to be lumps, abrupt ridges, and excessive and clumsy thickness of material where the woven fabric and leather are united. In boots and shoes made wholly of 10 leather the difficulty is overcome by skiving, but such method cannot be pursued when elastic woven fabric is used; and the object of my invention is to overcome the difficulty in boots and shoes composed partly of elastic 15 woven material. To this end the invention consists in an elastic woven fabric having a margin of gradually-diminishing thickness toward and to the selvage.

The structure or texture of the fabric may 20 be varied; but in carrying out my invention the fabric which is the subject of my United States Letters Patent No. 216,328, dated June 10, 1879, may be very advantageously adopted, and I have selected that fabric for the illustration of my invention.

Figure 1 is a longitudinal section of the body of the fabric. Figs. 2, 3, and 4 are longitudinal sections of the fabric, which are taken successively on lines nearer to the selvage.

Fig. 1 shows the body fabric to contain four warps—viz., the elastic warp, the india-rubber threads of which are represented by the heavier unbroken lines A, the face-warp, the 25 threads of which are represented by the heavier dotted lines B, the back warp, the threads of which are represented by the lighter dotted lines C, and the binder-warp, the threads of which are represented by the lighter unbroken lines. Fig. 2 shows the commencement of the

reduction of thickness by the omission of the back warp only. Fig. 3 shows a further reduction, nearer the edge, by leaving out not only the back warp but the elastic warp. Fig. 4 shows a still further reduction, nearer the edge, and which is intended to be continued to the selvage, by leaving out the elastic warp and alternate threads of the face-warp, leaving the fabric near and close to the selvage composed only of the weft, the binder-warps, and a small portion of the face-warp.

By thus omitting certain of the warp-threads, commencing at a point, say, half an inch from the selvage, and omitting more and more toward the selvage, a gradual reduction of the thickness of the fabric is effected, and a tapering of the margin substantially like that effected in leather by skiving is produced. The gradual reduction or tapering of the margin of the fabric in this manner provides for the production of a thick, soft, and cushion-like fabric, which is very suitable for those portions of boots and shoes which are required to be elastic and soft, and which can, notwithstanding its great thickness, be so joined to the leather and lining as to enable a very neat finish to be made where the rubber, the leather, and the lining come together.

What I claim as my invention, and desire to secure by Letters Patent, is—

1. An elastic woven fabric having a margin of gradually-diminishing thickness toward and to the selvage, substantially as described.

2. The elastic fabric herein described, containing in its body elastic warps and binder-warps, a face-warp with terry-loops, and a back warp with terry-loops and having its margin gradually reduced in thickness by the omission of the back warp, the elastic warp, and portions of the face-warp, substantially as herein described.

WILLIAM ELLIS JEFFERSON.
